[57] CLAIM

The ornamental design for a grip for a faucet handle, as shown and described.

DESCRIPTION

FIG. 1 is a perspective view of a faucet handle showing my new design;

FIG. 2 is a side elevational view thereof, the opposite side being a mirror image of the side shown;

FIG. 3 is a front elevational view thereof;

FIG. 4 is a side elevational view taken 90 degrees from the side shown in FIG. 2, the opposite side being a mirror image of the side shown; and

FIG. 5 is a rear elevational view thereof.
